FIREARM LOCK

Camille Parker, Montague City, Mass.

Application September 3, 1941, Serial No. 409,410

4 Claims. (Cl. 42—1)

The present invention relates to new and useful improvements in firearm locks particularly for guns, revolvers, automatic pistols, etc., and has for its primary object to provide, in a manner as hereinafter set forth, a device of this character which will positively prevent loading of the firearm.

Another very important object of the invention is to provide a lock of the aforementioned character comprising novel means for maintaining the bore of the barrel of the firearm in a clean, well-lubricated condition.

Other objects of the invention are to provide a firearm lock of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in vertical longitudinal section through a lock constructed in accordance with the present invention, showing the device in use on a revolver, portions of the latter being broken away in longitudinal section to reveal the invention.

Figure 2 is a view in side elevation of the lock.

Figure 3 is a top plan view.

Figure 4 is a view in front elevation of the device.

Figure 5 is a view in rear elevation of the block or body which is mounted on the forward end portion of the firearm barrel.

Figure 6 is a perspective view of the rear end portion of the rod constituting a portion of the device.

Figure 7 is a view in longitudinal section through a modification.

Referring now to the drawings in detail, it will be seen that reference numeral 1 designates a body or block of suitable metal, said body being substantially oval in cross-section, as shown to advantage in Figures 4 and 5 of the drawings. The body 1 has formed in its rear end portion a socket 2 for the reception of the forward end portion of the barrel 3 of a revolver 4. A longitudinal slot 5 in the upper portion of the body 1 communicates with the socket 2 and accommodates the sight 6 of the revolver 4. Thus, the

body 1 is positively secured against rotation on the barrel 3.

Extending longitudinally through the upper portion of the body 1 and slidably adjustable therein is a bolt or rod 7 of suitable metal. The rod 7 is adapted to extend through the barrel 3 into the chamber 8 of the cylinder 9 of the revolver 4 which is aligned with said barrel. An oiled cover 10 of felt or other suitable absorbent material is provided on the rod 7 for keeping the bore of the barrel clean and for preventing rust. On the forward end of the rod 7 is a roughened head 11.

The head 11 is removable.

15 Mounted on the rear end portion of the rod 7 is a thimble 12 which is engageable in the chamber 8. Extending into the thimble 12 from the rear end thereof are slots 13 for the reception of a cross-pin 14 which is mounted on the rear end portion of the rod 7. Thus, the rod 7 is connected to the thimble 12. Stop flanges 15 on the rear end of the thimble 12 are engageable with the corresponding end of the revolver cylinder 9.

20 The forward end portion of the rod 7 has milled therein a series of notches or recesses 16. Mounted in the forward end portion of the body 1 is a cylinder lock 17 which is operable by a key 18. The bolt 19 of the lock 17 is engageable selectively in the notches, or recesses 16, for positively securing the rod 7 against longitudinal movement relative to the body 1.

25 It is thought that the manner in which the device functions will be readily apparent from a consideration of the foregoing. Briefly, the rod 7 positively prevents rotation of the revolver cylinder 9 and also renders it impossible to load the chamber of said cylinder which is aligned with the barrel 3. When the device is used on other types of firearms loading of the breech is

30 prevented by the presence of the thimble 12 therein. To remove the lock the bolt 19 of the cylinder lock 17 is disengaged from the rod 7 and head 11 is removed. This permits the body 1 to be slipped forwardly off the rod 7, after which the thimble 12 with the rod 7 may be withdrawn rearwardly from the gun. The construction and arrangement is such as to substantially prevent dirt, water, etc., from getting into the barrel 3 of the firearm. Further, as hereinbefore indicated, the oiled cover 10 keeps the bore of the gun barrel thoroughly lubricated.

35 In the modification illustrated in Figure 7 of the drawings, an adapter sleeve 20 has a thimble 21 pressed thereinto. The rear end portion of the thimble 21 is longitudinally slotted, as at

22, to accommodate the pin 14. Then, the rear end portion of the sleeve 20 is provided with an external stop flange 23. By the use of thimbles of various thicknesses or external diameters the device may be successfully used on guns of different calibers.

It is believed that the many advantages of a firearm lock constructed in accordance with the present invention will be readily understood and although preferred embodiments of the device are illustrated and described, it is to be understood that changes in the details of construction and in the combination and arrangement of parts may be resorted to which will fall within the scope of the invention as claimed.

What is claimed is:

1. A firearm lock comprising a rod for insertion through the barrel of a firearm, a thimble on one end portion of said rod engageable in the firing chamber of the firearm, said thimble having slots extending therewith from its rear end, a cross-pin on the rod engaged in the slots for connecting said rod to said thimble, and means for anchoring the rod in the barrel.

2. A firearm lock comprising a rod for insertion through the barrel of a firearm, means for

5 anchoring one end portion of said rod in the firing chamber of the firearm, a body having a socket therein for the reception of the forward end portion of the barrel, the rod extending slidably through said body, and means in the body for locking the rod thereto against relative sliding movement.

3. A firearm lock comprising a rod for insertion through the barrel of a firearm, means on 10 one end of the rod for anchoring said rod in the firing chamber of the firearm, means for anchoring said rod in the barrel, and an absorbent lubricating sleeve on the rod for insertion in the barrel.

15 4. A firearm lock of the character described comprising a body having a socket therein for the reception of the forward end portion of a firearm barrel, said body further having a slot therein communicating with the socket for the 20 reception of a sight on the barrel, a rod insertible through the barrel and extending through the body, means for anchoring one end of the rod in the firing chamber of the firearm, and means for locking the other end portion of the rod to the body.

CAMILLE PARKER.
